CLAIM

The ornamental design for a camera, as shown and described.

DESCRIPTION

FIG. 1 is a front, top and right side perspective view of a camera showing our new design according to a first embodiment;

FIG. 2 is a front, bottom and left side perspective view thereof;

FIG. 3 is a rear, top and left side perspective view thereof; FIG. 4 is a rear, bottom and right side perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof;

FIG. 10 is a bottom plan view thereof;

FIG. 11 is a front, top and right side perspective view of a second embodiment of the camera illustrated in FIGS. 1-10; FIG. 12 is a right side elevational view thereof;

FIG. 13 is a front elevational view of a third embodiment of the camera illustrated in FIGS. 1-10;

FIG. 14 is a left side elevational view of a fourth embodiment of the camera illustrated in FIGS. 1-10; and,

FIG. 15 is a top plan view of a fifth embodiment of the camera illustrated in FIGS. 1-10.

The broken lines depict portions of the camera in which the design is embodied that form no part of the claimed design.

1 Claim, 15 Drawing Sheets
